UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 25, 1922, Serial No. 546,751. Renewed April 4, 1925.

The invention relates to drink mixers.

In machines for this purpose, the liquid constituents of the drink to be mixed are usually poured into a receptacle which is generally designated a "shaker," from many different containers disposed away from the mixer. The receptacle with these constituents therein is brought to the mixer and placed in operative relation thereto and is removed from the machine after each mixing operation, to discharge its contents. This is rendered necessary, because so many different ingredients and flavors are used in making drinks that they are, in nearly all cases, mixed individually. It is usually necessary to run the agitator for a considerable period to properly blend or mix the constituents and, therefore, it is desirable that provision be made for retaining the receptacle and agitator in operative relation to permit the dispenser to perform other duties during the mixing operation. In drink mixing, it thus becomes necessary to frequently place the receptacle containing the constituents into cooperative relation to the agitator and to withdraw it from the machine to discharge its contents and cleanse the receptacle between mixing operations.

A desideratum in this art is to expedite and simplify the operations necessary to bring the receptacle and agitator into cooperative relation, to maintain them in such relation, in starting and stopping of the motor and the removal of the receptacle. Heretofore, in machines whereof I am aware (excepting in those exhibited in concurrently pending applications), it has been necessary in their use to manually manipulate the receptacle into operative position and withdraw it therefrom and to additionally perform some separate step or operation, such as lowering the motor and agitator together, or shifting the agitator and its shaft into the receptacle and relatively to the motor; or raising and locking a receptacle-support to establish and maintain cooperative relation of the receptacle and agitator or to control the operation of the machine. Another desideratum in this art is to simplify the machine by dispensing with movable connections in and for the driving mechanism for the agitator.

One object of the present invention is to provide an improved drink mixer in which these additional operations or steps are dis-

pensed with and in which manual shift of the receptacle is utilized to completely control the operation of the machine and to secure it and the agitator in cooperative relation. By dispensing with the necessity of these additional steps or operations, the time of the dispenser in performing them is saved and the service is improved.

Another object of the invention is to provide an improved drink mixer in which provision is made for the ready removal and replacement of the motor and all of its electrical connections. In practice, it has been found that the motor and electrical connections therefor sometimes get out of order, while the remaining mechanism does not. When motor or electrical repair is necessary, it has been customary to send the entire machine to the repair shop. The present invention contemplates mounting the switch directly on the outside of the motor casing, so that when the motor is removed, all electrical connections will remain attached thereto, so that another motor with connections may be readily substituted while the repairs are being made in the shop, without the necessity of making any electrical connections at the machine.

Another object of the invention is to provide a receptacle-operated machine, in which the receptacle, during the mixing operation, is yieldingly held between bottom and top supports. Other objects of the invention will more fully appear from the following description.

The invention consists in the several novel features hereinafter set forth and more particularly defined by claims at the conclusion hereof.

In the drawings: Fig. 1 is a side elevation of a machine embodying the invention, the receptacle-holder being shown in lowered or idle position. Fig. 2 is a plan, the cover of the switch-box being shown in section. Fig. 3 is a section on line 3—3 of Fig. 1. Fig. 4 is a vertical section of the machine, the receptacle being shown in operative position. Fig. 5 is a detail showing the manner of locking the carrier to secure the receptacle in its operative position.

The invention is exemplified in a machine comprising an electric motor 10 to the rotor of which is secured a pendant shaft 11 with an agitator 12 fixed to its lower end; a support framework comprising a base 9 adapted

to rest on a table or counter, a pair of separated vertical rods or standards 13 having their lower ends fixedly secured in said base, and a bracket 16 in which the upper ends of rods 13 are secured and which is provided with lugs 14 to which the casing of the motor 10 is removably secured by screws 14^a; and a box 15 containing a switch for controlling the operation of the motor. Shaft 11 is of sufficient length so that the agitator will reach into the constituents of a drink to be mixed near the bottom of an open-top receptacle *a* held below the motor. There is sufficient clearance below and around the agitator to permit the receptacle to be placed therebeneath without spilling its contents and without lowering the agitator into the receptacle so that it is not necessary to vary the relationship between the agitator and the motor or between the agitator and the machine base in establishing cooperative relationship between the receptacle and the agitator.

In the present invention, a carrier in which the receptacle is locked is vertically slideable on the standards 13 and comprises a standard 17, a lower cross-member 17^a, which is provided with holes 17^b through which the rods 13 pass, and an upper cross-member 18 which is provided with holes 18^a through which said rods also pass. Lugs 20' are formed on the rear portion of the rods 13 directly behind notches 19 in the front of the rods and are adapted to engage and support the cross-member 18 to lock the carrier in its raised position. The portions 20 of the rods which are above the notches 19 operate as stop lugs and limit the upward movement of the carrier. A bottom-support 22 for the receptacle *a*, which may be an ordinary glass tumbler if desired, is adjustably secured to the standards 17 by screws 23 and slots 24. The purpose of this adjustable connection is to permit the bottom support to be adjusted to support the bottom of the receptacle the desired distance from the agitator 12. In some instances, it is desirable to operate the agitator different distances from the bottom, according to the materials to be mixed. An upper holder ring 25 is adapted to engage the upper edge of the receptacle *a* and has a convex lower face 26, so that its central portion will extend into the receptacle and tend to position the glass around the agitator and hold it against lateral movement. The upper holder 25 is provided at its back with downturned lugs 27 which are pivotally connected by a pin 28 to lugs 29 on a bracket 30 which is adjustably secured to standard 17 by screws 31 and slots 32. The purpose of the adjustable connection between said bracket and standard is to permit the holder-member 25 to be adjusted for receptacles of different heights. The spring 33 is coiled around pivot-pin 28 and is applied to press the holder 25 downwardly against the upper edge of the receptacle. A

stop-arm 34 is provided to limit the downward movement of the holder so that it will be positioned to permit the receptacle *a* to be inserted between support 22 and the holder. The central portion of support 22 is flared 70 downwardly, as at 22^a, to guide the receptacle onto said support. This holder member 25, as shown in the drawing, fits against the rim of the receptacle and extends inwardly thereof so that it functions also as a spring-pressed cover, it being understood that in practice the vortex causes the highest portion of the liquid column to be adjacent the wall of the receptacle. 75

The switch-box 15, formed of insulating material, is secured by screws 35 directly to the outside of the casing of motor 10 and comprises a cover 36 which is removably secured thereto by screws 37. Conductor strips 38 and 39 project from one side of the box and are adapted to enter a switch-socket of usual construction and to which a flexible conductor-cord is usually connected. Strip 39 is provided with a lug 40 which is secured in the box by a screw 41. A conductor 42 leads from said screw to one end of the motor-windings. A conductor 43 leads from the other end of said windings to a screw 44 which secures a switch-contact 45 in the box. 80 A strip 38 is provided with a lug 46 which contacts with a spring-contact strip 47 and both of said strips are secured in the box by screw 48. A button 49 is slidably held in the box and is connected to contact-strip 47 by a screw 50 which is adapted, when the button is raised, to engage with the underside of resilient contact 45 to close the circuit through the motor. When the button 49 is lowered, the circuit is interrupted at contact 45 and screw 50. A lever 51 is pivoted at 85 its lower end to a cross-bar 52 which is secured to the supporting rods 13 and the upper end of said lever is provided with a cam-surface 53 which is adapted to engage switch-button 49 to force it upwardly to close the circuit for the motor. A cam 54 on said lever is adapted to be engaged by the upper cross-member 17^a of the receptacle-carrier holder to force the lever backwardly while the receptacle is being lifted into its operative position, 90 and to hold it while the carrier is raised, and to permit the lever to be retracted by a spring 56 during the lowering of the receptacle for withdrawal from the machine. 95

The operation of the machine will be as follows: Normally, the carrier will be in lowered position shown in Fig. 1. The operator, grasping the receptacle, will place its upper end under the spring-pressed holder member 25 and swing its lower portion backwardly onto the bottom-support 22 and then lift the carrier through the receptacle until the carrier slips over locking lug 20'. Thereupon, the carrier will be locked to hold the receptacle in its operative position, as shown in 100

Fig. 5. During the upward shift of the carrier, lever 51 will be operated to close the switch and cause the motor to drive the agitator. During the operation of the motor, the receptacle will be gripped and centralized between the bottom support 22 and the yielding upper member 25. After the mixing operation has been completed, the operator will grasp the receptacle and force it backwardly sufficiently to disengage the carrier from the lug 20' and then lower the receptacle. While the carrier is locked in operative position, it will hold the lever 51 in position to keep the switch closed. During the descent of the carrier, the switch-lever will be released by the carrier and retracted by spring 56 to open the switch and stop the motor.

The invention exemplifies a drink mixer which is controlled by manual placement and removal of the receptacle into a holder comprising top and bottom members between which the receptacle will be resiliently gripped, and in which provision is made for adjusting the bottom support for the receptacle relatively to the agitator; in which the switch-box for controlling the motor is secured on the outside of and to the motor casing, so that all the electrical connections are removable with the motor for convenience in making repairs and substitution of one motor for another; in which the switch-box is provided with strips adapted to engage directly with a switch-socket so that no flexible cord is necessary on the machine; in which the motor support is made up of rods secured together and upon which the receptacle-holder is adapted to slide.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of a support, an electric motor removably mounted on said support, an agitator driven by the motor, said motor and agitator being stationarily mounted with respect to said support, means for removably holding a receptacle in operative position around the agitator, a switch for controlling the motor mounted on the outside of the motor casing and removable therewith and automatic means for shifting the switch when the receptacle and agitator are brought into operative relation.

2. In a machine of the character described, the combination of a support, an electric motor removably mounted on said support, an agitator driven by the motor, said motor and agitator being stationarily mounted with respect to said support, means for removably holding a receptacle in operative position

around the agitator, a switch for controlling the motor, means for connecting the switch to a switch-socket, said switch and connecting means being mounted on the outside of the motor casing and removable therewith and 70 automatic means for shifting the switch when the receptacle and agitator are brought into operative relation.

3. In a machine of the character described, the combination of a support, an electric 75 motor removably mounted on said support, an agitator driven by the motor, said motor and agitator being stationarily mounted with respect to said support, means for removably holding a receptacle in operative 80 position around the agitator, a switch for controlling the motor mounted on the outside of the motor casing and removable therewith, switch-shifting means mounted on said support and from which said switch is separable. 85

4. In a machine of the character described, the combination of a support, an electric motor removably mounted on said support, an agitator driven by the motor, said motor and agitator being stationarily mounted with 90 respect to said support, means for removably holding a receptacle in operative position around the agitator, a switch for controlling the motor mounted on the outside of said case and removable therewith and contacts for engaging an ordinary switch-socket rigidly secured to the switch and removable therewith. 95

5. In a machine of the character described, the combination of a support, an electric 100 motor removably mounted on said support, an agitator driven by the motor, said motor and agitator being stationarily mounted with respect to said support, means for removably holding a receptacle in operative position around the agitator, a switch-box mounted on 105 and removable with the outside of the motor casing, a switch in said box, and contacts for engaging an ordinary switch-socket mounted in said box.

6. In a machine of the character described, the combination of a support, an electric 110 motor removably mounted on said support, an agitator driven by the motor, means for removably holding a receptacle in operative position around the agitator, a switch-box 115 secured to the outside of and removable with the motor-casing, switch-members mounted in said box, a button for operating the switch mounted in the box, and means for operating the button mounted on said support and permitting independent removal of the switch-box. 120

7. In a machine of the character described, the combination of a support, an electric 125 motor mounted on the support, an agitator driven by the motor, and means for removably holding a receptacle in operative position around the agitator comprising members for engaging the upper and lower portions of the receptacle, the upper member

being normally disposed to prevent the receptacle from striking the agitator, and means for pressing one of the members towards the other to yieldingly hold the receptacle.

5 8. In a machine of the character described, the combination of a support, an electric motor mounted on the support, an agitator driven by the motor and means for removably holding a receptacle in operative position around the agitator comprising members for engaging the top and bottom of the receptacle, the upper member being normally disposed to prevent the receptacle from striking the agitator and spring means for pressing 10 the upper member against the top of the receptacle.

9. In a machine of the character described, the combination of a support, an electric motor mounted on the support, an agitator 20 driven by the motor, and means for removably holding a receptacle in operative position around the agitator comprising a lower supporting member, and a member for engaging the top of the receptacle formed with 25 a concave portion to laterally position the receptacle around and normally disposed to prevent the receptacle from striking the agitator.

10. In a machine of the character described, 30 the combination of a support, an electric motor mounted on the support, an agitator driven by the motor, and means for removably holding a receptacle in operative position around the agitator comprising a supporting member for the bottom of the receptacle and a spring-pressed member for engaging the top of the receptacle and pivoted at one side of the receptacle to press it towards the lower member.

40 11. In a machine of the character described, the combination of a support, an electric motor mounted on the support, an agitator driven by the motor, and means for removably holding a receptacle in operative 45 position around the agitator shiftable vertically by manual manipulation of the receptacle itself and comprising a vertically movable carrier, a support on the carrier for the bottom of the receptacle, and a member for 50 engaging the top of the receptacle, and means for yieldingly pressing the upper member against the receptacle.

12. In a machine of the character described, 55 the combination of a support, an electric motor mounted on the support, an agitator driven by the motor, and means for removably holding a receptacle in operative position around the agitator shiftable vertically by manual manipulation of the receptacle itself and comprising a member for 60 engaging the top of the receptacle and a member for engaging the bottom of the receptacle, and means for adjusting the bottom member to vary the position of the bottom 65 member of the receptacle with respect to the agitator.

13. In a machine of the character described, the combination of a support, an electric motor mounted on the support, an agitator driven by the motor, and means for removably holding a receptacle in operative 70 position around the agitator shiftable vertically by manual manipulation of the receptacle itself and comprising a vertically movable carrier, a member for engaging the bottom of the receptacle adjustably connected to the carrier so its position relative to the agitator may be varied, and a member on the carrier for engaging the top of the receptacle.

14. In a machine of the character described, 80 the combination of a base, a pair of supporting rods rigid with the base, an electric motor secured to the upper ends of said rods, an agitator driven by and suspended from the motor, and means carried by the rods for removably holding the receptacle in operative position around the agitator.

15. In a machine of the character described, 90 the combination of a base, a pair of supporting rods rigid with the base, an electric motor secured to the upper ends of said rods, an agitator driven by and suspended from the motor, and means vertically movable on the rods for holding the receptacle in operative position around the agitator.

16. In combination, a support, a cover yieldingly carried by said support, a cup adapted to engage and to be held at its upper end by entering into the embrace with said cover and a step for receiving and sustaining the lower end of said cup, said cover and step each holding the cup in engagement with the other and being adapted to receive and hold the cup in its operative position by its own manipulation.

17. In combination, a support, a cover yieldingly carried by said support, a cup adapted to engage said cover by an upward movement and to be sustained at its upper end by said cover, and a step receiving the lower end of said cup by lateral movement and sustaining the cup in engagement with the cover; the step and cup being adapted to interengage by relative vertical movement permitted by the yielding of the cover.

18. In a machine of the character described, the combination of a support, an electric motor mounted on said support, an agitator mounted to rotate in a position substantially fixed with respect to the motor, and means to automatically retain the receptacle in its cooperative relation with the agitator upon manual manipulation of the receptacle itself into such position, comprising a bottom supporting member and a yielding cover member to engage the receptacle rim and extend into the top thereof.

19. In a drink mixer, the combination of a motor, an agitator shaft, and means for holding a receptacle in its operative position

comprising a cover-element for engaging the top of the receptacle, a supporting element for engaging the bottom of said receptacle, the elements being normally co-relatively spaced so the receptacle can be inserted into position to be retained therebetween by manipulation of the receptacle itself, one of the elements being spring pressed so the cover-element will be held against the top of the receptacle, and means for automatically controlling the operation of the motor operable by manual manipulation of said receptacle.

20. In a drink mixer, the combination of a motor, an agitator driven by the motor, and means for holding a receptacle in its operative position comprising a bottom supporting element and an upper retaining element, one of which is spring-pressed to clamp the receptacle vertically between said elements, said elements being normally co-relatively spaced to grip the receptacle and separable by manual manipulation of the receptacle itself.

21. In a drink mixer, the combination of a motor, an agitator driven by the motor, and means for holding a receptacle in its operative position comprising a bottom supporting element and an upper retaining element, said upper retaining element being spring-pressed downwardly toward the lower supporting element, said elements being normally co-relatively spaced to grip the receptacle and separable by manual manipulation of the receptacle itself.

35 22. In a drink mixer, the combination of a motor, an agitator driven by the motor, means for holding a receptacle in its opera-

tive position comprising a bottom supporting element and an upper retaining element, one of which is spring-pressed to clamp the receptacle vertically between said elements, said elements being normally co-relatively spaced to grip the receptacle and separable by manual manipulation of the receptacle itself, and means for controlling the motor, operable by manual manipulation of the receptacle.

23. In a drink mixer, the combination of a motor, an agitator driven by the motor, a support for the motor, a cover, a step disposed below the cover, and a receptacle adapted to engage the cover by an upward movement, and to be moved laterally onto the step and to be retained between the step and the cover, said cover and step being normally co-relatively spaced to grip the receptacle and separable to receive the receptacle by manual manipulation of the receptacle itself.

24. In a drink mixer, the combination of a motor, an agitator driven by the motor, a support for the motor, a yieldingly supported cover, a supporting step below the cover, and a receptacle adapted to engage the cover by an upward movement and to be moved laterally onto the step, and to be retained between the step and the cover, said cover and step being normally co-relative to grip the receptacle, and separable by the upward manual manipulation of the receptacle against the cover.

Signed at Newark, N. J., this 11th day of February, 1922.

RAYMOND B. GILCHRIST.
